No. 824,020.

PATENTED JUNE 19, 1906.

W. D. JACKSON.
TRACK TORPEDO.
APPLICATION FILED APR. 21, 1905.

UNITED STATES PATENT OFFICE.

WILTON D. JACKSON, OF PHILADELPHIA, PENNSYLVANIA, ASSIGNOR TO
FRANK DUTCHER, OF VERSAILLES, PENNSYLVANIA.

TRACK-TORPEDO.

No. 824,020.

Specification of Letters Patent.

Patented June 19, 1906.

Application filed April 21, 1905. Serial No. 286,718.

To all whom it may concern:

Be it known that I, WILTON D. JACKSON, a citizen of the United States, residing in Philadelphia, Pennsylvania, have invented certain 5 Improvements in Track-Torpedoes, of which the following is a specification.

My invention relates to torpedoes designed to be placed upon railway or trolley tracks to serve as signals for approaching trains or 10 cars.

The object of my invention is to provide an 15 efficient torpedo made of fibrous or other non-metallic material and one that will act under all conditions and will be absolutely harmless when exploding.

A further object of my invention is to provide a torpedo of non-metallic material, whether inclosed in a casing or not, but having 20 a waterproof coating or covering, with means wholly independent of the torpedo 25 itself for securing it to the head of a rail and means wholly exterior of the torpedo for confining said securing means thereto. The confining means embrace or encircle the torpedo, 30 binding the securing-strap thereto, and such confining means are preferably fibrous and are either in the shape of a cord or string or a strip or strips of paper, fabric, or vegetable fiber, which may be temporarily secured in 35 place by glue, and in the final treatment of the torpedo held against displacement by the waterproof coating or covering of the same.

My invention is fully shown in the accompanying drawings, in which—

Figure 1 is an inverted perspective view 35 showing in full size my improved torpedo just prior to completion. Fig. 2 is an enlarged cross-sectional view of the same, taken on the line *a a*, Fig. 1. Fig. 3 is an enlarged 40 cross-sectional view taken on the line *b b*, Fig. 1. Fig. 4 is an inverted perspective view of the finished torpedo, the outer surface having been coated with a waterproofing material. Fig. 5 is a view of the 45 torpedo in position upon a rail, the latter being shown in section; and Figs. 6, 7, 8, 9, and 10 are views illustrating modifications of my invention.

The essential object of my invention is to 50 provide a track-torpedo designed to serve as a signal in railroading that will be absolutely harmless. As heretofore constructed track-torpedoes have usually been made of metal, and accidents have frequently happened due

to the flight of portions of the metal forming 55 the torpedo during or succeeding the explosion of the same.

The torpedo made in accordance with my invention consists of a suitable receptacle which may be a round box-like structure 1, 60 as shown in Figs. 1, 2, 3, and 4, and comprises telescoping members 2 and 3, which when placed together inclose the explosive or detonating material 4. These sections 2 and 3 may be of paper, fabric, papier-mâché, 65 wood, or other similar substance suitably prepared for use and when finished rendered waterproof by any suitable means before or after the detonating material is placed within the structure. Other shapes may be employed—such as the square box shown in Fig. 6, the envelop shown in Fig. 7, the convex structure shown in Fig. 8, or a tubular device with crushed ends shown in Fig. 9. Torpedoes of this general character 70 require some means for holding them to the rail, and such means usually consist of a strip of flexible material, preferably lead, which is indicated at 5 in the accompanying drawings. This strip of lead may be held to the 75 torpedo in a number of ways; but I prefer to pass it under the structure forming the torpedo and secure it by means, preferably a string or thread 6, passing around or over the torpedo, thereby confining such lead strip 80 thereto. In the structures shown herewith this confining means, consisting of thread, string, or similar material, is wrapped or passed several times around the box, crossing, preferably in both directions, the strip of 85 lead, and the ends of the string are retained temporarily in position by glue or other similar material. This string or other material serves to retain the lead strip in place, and when the torpedo is dipped in a waterproofing composition of any suitable character it 90 will inclose the retaining-string and the portion of the lead strip lying against the torpedo and will secure the latter firmly to the torpedo, at the same time fully covering and 95 protecting the material of which the torpedo is composed and, while rendering it damp and waterproof, not affecting its explosive properties.

My improved torpedo is of fibrous or other 100 non-metallic material, and when it is exploded there will be no danger from the flying fragments, as they will have little or no

force. To obviate the danger of causing the securing-strap to be blown about by the force of the explosion, such strap, which is of metal, lead being preferred, lies wholly under the torpedo when the latter is secured to the head of a rail, and the explosion tending to elevate the cover or casing inclosing the detonating material there will be no danger of portions of the retaining-strip flying around promiscuously. Another reason for locating the securing - strip and its retaining means wholly exterior of the torpedo is to insure that the envelop or cover of the latter will not be pierced by the retaining means or injured by the displacement of the latter when packed for shipment, stored in the caboose or other car, or carried in the pocket of the brakemen.

In the torpedo shown in Fig. 6 the securing-strap is held in place by a band of paper or fabric 7, and in that shown in Fig. 7 a string or cord is simply passed around both ends of the lead strip at 8 and then back across the top of the torpedo and held by glue until the waterproof material is added.

In the substantially flat forms of the torpedo which I have shown I prefer to secure the lead strip in place by some such retaining means, but in the tubular form shown in Fig. 9 I hold the lead strip in place by means of string wrapped around the tube or by independent bands or strips 9 of paper, fabric, or other fibrous material, very much in the same manner as disclosed in my prior application, filed December 26, 1903, Serial No. 186,724.

In Fig. 10 I show a form of torpedo made of the detonating material compressed into shape and having a securing-strap passed across its under side and confined in place with a wrapping of string which passes entirely around the torpedo. This structure is then dipped in the waterproofing composition. To make sure of a waterproof covering, it may also be dipped before the strap is secured in place.

Excepting Fig. 4, all of the torpedoes shown herewith are without the waterproof coating or covering, although it will be understood that all forms are to be so finished. The waterproofing composition is preferably of such character as to fully coat the exterior of the torpedo and confine the lead strap as well as the securing string or cord and the loose ends of the same to the torpedo-casing.

Having thus described my invention, I claim and desire to secure by Letters Patent—

1. As a new article of manufacture, a track-torpedo comprising a casing of paper having a filling of detonating material exploding under pressure, means for securing said torpedo to the head of a rail, and a cord passing around the body of said torpedo and serving to hold the securing means thereto.

2. As a new article of manufacture, a non-metallic track-torpedo having a filling of detonating material, means for securing said torpedo to the head of a rail, means passing around the body of said torpedo for retaining the securing means thereto, and a coating of plastic material for confining the securing means and the retainer for the latter.

3. As a new article of manufacture, a non-metallic track-torpedo having a filling of detonating material, means for securing said torpedo to the head of a rail, means passing around the body of said torpedo for retaining the securing means thereto, and a coating of waterproof material for confining the securing means and the retainer for the latter to the torpedo.

4. As a new article of manufacture, a non-metallic track-torpedo having a filling of detonating material, means for securing said torpedo to the head of a rail, and a plastic coating for the body of said torpedo for retaining said securing means thereto.

5. As a new article of manufacture, a track-torpedo comprising a casing of paper having a filling of detonating material exploding under pressure, means for securing said torpedo to the head of a rail, a cord passing around the body of said torpedo and serving to hold the securing means thereto, and means for holding said cord against displacement.

6. As a new article of manufacture, a non-metallic track-torpedo comprising a circular several-part case made of fibrous material, and fibrous means passing diametrically around the case to hold the parts of the same together.

7. As a new article of manufacture, a track-torpedo comprising a fibrous case composed of circular telescoping members, and retaining means passing diametrically around the same and serving to hold them together.

8. As a new article of manufacture, a track-torpedo comprising in combination, a fibrous case composed of circular telescoping members, a strap for securing it to the head of a rail, and retaining means passing diametrically around the parts of the structure and serving to hold them together.

9. As a new article of manufacture, a track-torpedo comprising a circular casing, a rail-engaging strap passed across the casing and disposed on one face only of the same, and means completely surrounding the case diametrically and embracing the rail-engaging member.

In testimony whereof I have signed my name to this specification in the presence of two subscribing witnesses.

WILTON D. JACKSON.
